UNITED STATES PATENT OFFICE.

JOHN F. L. BAKER, OF SAGINAW, MICHIGAN, ASSIGNOR TO WICKES BOILER CO., OF SAGINAW, MICHIGAN, A CORPORATION OF MICHIGAN.

CYLINDER-FORMING MACHINE.

Application filed February 23, 1927. Serial No. 170,191.

This invention relates to plate bending and forming machines that are used for bending heavy steel plates into cylindrical form, as in the manufacture of steel drums for high pressure water tube boilers. The plates used for this purpose are frequently as thick as one and a quarter to two inches, the width of the sheet, or length of the drum, commonly being ten feet or greater, and the diameter 10 of the cylinder to be formed from it, say, forty two inches or larger.

It is not practicable to form such heavy material into cylinders of such relatively small diameter and great length by rolling. 15 My invention, therefore, relates more particularly to a forming machine in which the plate is subjected to successive and progressive bending operations between a fixed anvil and a co-operating die. 20 The invention is, therefore, applicable to forming machines of the general character above referred to, in which a long beam-like stationary anvil, formed with a longitudinal groove in its upper or working face co-operates with a beam-like die member arranged 25 parallel with the anvil and adapted to operate therewith.

In operation, the plate is laid on the anvil and is gradually fed through the machine 30 while the die member progressively presses it into the groove of the anvil, slightly bending it at each operation.

Heretofore it has been customary in machines of this kind to form the groove in the die and to provide a co-operating rib on the working face of the anvil. In such machines the plate is made to curl downward and when the cylinder is completed it encloses 35 the anvil, making it necessary to provide an opening or passageway in the base of the anvil to permit the cylinder to form. It is also necessary to provide means for stripping the completed cylinder from the stationary anvil, and that construction obviously involves a weakening of the anvil structure and distinctly limits the capacity of 40 the machine for handling very thick and very wide work, because it is impossible to spring open the heavy drum sufficiently to take it off the anvil.

The object of my invention is to provide a machine of the anvil and reciprocating die type that will quickly and accurately produce cylinders from very heavy plates, say, 45 up to three inches thick, ten to thirty feet in

length and of relatively small diameter, say, thirty-six inches.

To attain that object I have invented certain novel features of construction and operation as follows: A plate-forming machine in 60 which the forming groove is in the anvil and the forming rib is on the die, so the plate will curl upward and forward as it is fed into the machine and in so doing will take the form of a cylinder that surrounds the 65 die instead of the anvil.

Great rigidity is attained in the die by mounting it in a movable frame comprising a very rigid strong-back arranged above and parallel with the die and having two downwardly projecting end members. In the lower ends of these end members the die is mounted, the strong-back and die spaced apart vertically to provide a passageway or clearance between them to receive the plate 75 as it curls upward and forward.

I also provide removable spacers or struts between the die and the strong-back to prevent any appreciable springing of the long die when subjected to heavy duty. 80

My invention also includes means for stripping the formed cylinder from the die, comprising a swiveled connection between one end of the die and one of the downwardly projecting end members of the strong-back, 85 and a detachable connection between the other end of the die and the other downwardly projecting strong-back member, whereby the latter connection can be unfastened, the die swung out horizontally and the cylinder 90 stripped off.

The improvement also includes novel means for supporting the free end of the die while the cylinder is being removed from it. The cylinders are very heavy, some weighing 95 many tons. I, therefore, provide means not only for supporting the free end of the die, when swung out, but also for providing an extension for use while the cylinder is being slid off from the end of the die. For that purpose 100 a removable stripping bar which can be temporarily attached to the end of the die is employed. The completed cylinder is slid from the die onto the stripping bar, after which the bar is disconnected from the die 105 which is then returned to its normal position while the completed cylinder, still on the stripping bar, can be removed by means of an overhead crane.

With the foregoing and certain other ob- 110

jects in view, which will appear later in the specifications, my invention comprises the devices described and claimed and the equivalents thereof.

6 In the drawings Fig. 1 is a side elevation partly broken away, showing a bending machine constructed according to my invention.

Fig. 2 is a transverse section on the line 2—2 of Fig. 1.

10 Fig. 3 is a detail of the swiveled connection between the movable die and the strong-back.

15 Fig. 4 is a diagrammatic top plan view of the die, its outward or open position shown by dotted lines.

Fig. 5 is a side view of the stripping bar or die extension member.

20 As is clearly shown in the drawings, the machine embodying my invention comprises a long beam-like stationary anvil 1 formed with a longitudinal groove 2 in its upper or working face, and a beam-like die member 3 parallel with the anvil and movable toward and from it.

25 In operation, the plate 4 is laid on the anvil, as shown in Fig. 2 and is gradually fed through while die member 3 repeatedly presses it into the groove 2 of the anvil, slightly bending it at each operation. The curled 30 part of the plate progresses rearwardly and upwardly, generating the first part of a cylinder 5 of small diameter, provided the die 3 is forced far down into the groove 2 of the anvil, or generating a cylinder 6 of larger 35 diameter if the die does not go so deep. In every instance the advancing edge of the curled plate passes forward over the top of die 3, and finally takes the form of a complete cylinder that surrounds the die, instead of a part cylinder that encloses the anvil, as in 40 the earlier machines heretofore referred to.

45 The die 3 is actuated by means of a frame comprising a rigid strong-back 7 arranged above and parallel with the die and having two downwardly projecting end members 8, 9, in the lower ends of which the die is mounted. The strong-back and die are spaced apart vertically to provide a passageway or clearance 10 to permit the plate 4 to pass through 50 while curling.

A preferred means for actuating the die-carrying frame is a hydraulic engine 11 at each end, having a reciprocating piston rod 12 connected to the strong-back 7.

55 To prevent springing of the die when subjected to extremely heavy duty I provide a number of removable spacers or struts 13 between the die and the strong-back 7. Preferably the top faces of the die are inclined from its middle part toward its ends, as shown at 14, the under face of the strong-back being straight. The struts 13 can be moved nearer the ends of the die when wider plates are to be worked. In that case shims 13a may be inserted between the bottom faces of struts 13

and faces 14 of the die, in the usual manner.

An end of the die swings outward in a horizontal plane, until it clears the machine, to permit the finished cylinder to be stripped from the die. For that purpose a swiveled 70 connection is provided between an end of the die 3 and one of the downwardly projecting members 8 of the strong-back 7.

This swiveled connection is designed to hold the die rigid while it is operating on the 75 work, and to permit it to be swung outwardly when a cylinder is to be removed, as shown by dotted lines in Fig. 4, without binding or straining the frame.

A preferred form of swiveled connection is 80 shown in Figs. 1 and 3, where 15 is the end of die 3, upon which rests a pair of bearing plates 16, 17, and between the plates is a hard metal shim 18 of somewhat elliptical cross-section. Both the shim 18 and the bearing plates 16, 17 85 are apertured for a pintle bolt 19 that holds die 3 securely to strut 8, but permits it to swing out as indicated in Fig. 4.

The shim 18 assures a close bearing between 90 strut 8 and end 15 of the die, and it also permits the die to have a limited amount of up and down movement at its free end without binding or unduly straining the joint or the die-carrying frame 7, 8, 9.

As previously stated, I provide a detachable 95 connection between the other end 20 of the die and the downwardly projecting strong-back member 9, so that after cylinder 5, or 6 has been formed the connection can be unfastened and the die can be swung out horizontally 100 to permit the cylinder to be stripped off.

The detachable connection is made by securing the end 20 of the die to the strong-back member 9 by bolts 21, as shown in Fig. 1.

Suitable means is also provided for supporting the free end 20 of the die while the cylinder 5 is being removed from it. The preferred supporting means is a loose truck 22 that runs on any suitable way 23.

To facilitate removal of a short heavy cylinder from the die, I provide a detachable independent extension support for the free end of the die. This support is a stripping bar 24 which can be temporarily attached to the end of the die by inserting it in a socket 25 110 formed therein. The completed cylinder is slid off from the die 1 onto the stripping bar 24, the outer end of the bar being meanwhile supported on a crane-hook, or any other convenient means. After stripping, the end of bar 24 can be disconnected from the die 1, the latter being returned to its working position, while the cylinder can be taken away by means of an overhead crane that picks up the two projecting ends of the stripping bar which 115 serves as a sling for carrying the cylinder away from the machine.

In the case of a very long cylinder the stripping bar is inserted as before, supported at its 120 outer end. The cylinder is then stripped off 125

until it is about half on the bar and half on the die. The die is then blocked up near its middle, as at 26 in Fig. 4. The stripping bar is then removed and the cylinder taken off.

5 The truck 22 is then placed under the end 20 of the die, and the die is run back into its normal working position and locked to the strong-back frame by bolts 21.

Having thus described my invention, what 10 I claim and desire to secure by Letters Patent is:

1. In a machine for forming a cylinder from a heavy metal plate, an anvil formed with a longitudinal groove in its working 15 face, a die disposed normally parallel with the groove of said anvil and adapted to move so as to press the plate progressively into said groove, whereby to cause the plate to encircle the die, means for actuating said die, 20 and a pivotal support for an end of said die, its other end adapted to be swung out from said normal position to permit removal of the completed cylinder.

2. In a machine for forming a cylinder from a heavy metal plate, an anvil formed with a longitudinal groove in its working 25 face, a movable die-carrying frame comprising a strong-back having downwardly projecting members near its ends, a die having 30 its ends mounted in said downwardly projecting members and disposed normally parallel with the anvil, said die adapted to press the plate progressively into said groove, said strong-back and die spaced apart to receive 35 the curved part of said plate between them, means for actuating said die-carrying frame, and means for detaching an end of said die from said frame to permit removal of the completed cylinder.

40 3. In a machine for forming a cylinder from a heavy metal plate, an anvil formed with a longitudinal groove in its working face, a reciprocating frame having a die disposed normally parallel with the groove of 45 said anvil and adapted to press the plate progressively into said groove, whereby to cause the plate to encircle the die, a pivotal connection between said reciprocating frame and an end of said die, the other end of the die adapted to be swung out from its normal 50 position in the frame to permit removal of the completed cylinder, and means for actuating said reciprocating frame

45 4. In a machine for forming a cylinder from a heavy metal plate, an anvil formed with a longitudinal groove in its working face, a reciprocating frame having a die dis-

posed normally parallel with the groove of said anvil and adapted to press the plate progressively into said groove, whereby to cause 60 the plate to encircle the die, a swivel connection between said reciprocating frame and an end of said die, said connection including a pintle bolt, a shim having its opposite faces bowed and a pair of bearing plates seated 65 against said faces, the other end of the die adapted to be swung out from its normal position in the frame to permit removal of the completed cylinder, and means for actuating said reciprocating frame. 70

5. In a machine for forming a cylinder from a heavy metal plate, an anvil formed with a longitudinal groove in its working face, a movable die-carrying frame comprising a strong-back having downwardly projecting side members, a die mounted in said side members and disposed normally parallel with the anvil, said die adapted to press the plate progressively into said groove, said strong-back and die spaced apart to receive 75 the curved part of said plate between them, removable struts connecting said strong-back and die, and means for actuating the die-carrying frame, for the purposes set forth. 80

6. In a machine for forming a cylinder from a heavy metal plate, an anvil formed with a longitudinal groove in its working 85 face, a die disposed normally parallel with the groove of said anvil and adapted to move so as to press the plate progressively into said 90 groove, whereby to cause the plate to encircle the die, means for actuating said die, a pivotal support for an end of said die, its other end adapted to be swung out from said normal position to permit removal of the 95 completed cylinder, and a stripping bar removably secured to said other end to temporarily receive said cylinder. 100

7. In a machine for forming a cylinder from a heavy metal plate, an anvil formed 100 with a longitudinal groove in its working face, a movable die-carrying frame comprising a strong-back having downwardly projecting side members, a die mounted in said side members and disposed normally parallel 105 with the anvil, said die adapted to press the plate progressively into said groove, said strong-back and die spaced apart to receive the curved part of said plate between them, and means for actuating the die-carrying 110 frame, for the purposes set forth.

In testimony whereof, I affix my signature.

JOHN F. L. BAKER.
